UNITED STATES PATENT OFFICE.

THEODORE LUCE, OF DETROIT, MICHIGAN.

RAILWAY-CAR.

SPECIFICATION forming part of Letters Patent No. 247,259, dated September 20, 1881.

Application filed March 8, 1881. (No model.)

To all whom it may concern:

Be it known that I, THEODORE LUCE, of the city of Detroit and State of Michigan, have invented an Improvement in Railway-Cars, of 5 which the following is a specification.

The nature of my invention relates to certain new and useful improvements in the construction of railway-cars, by means of which bar and sheet steel or iron, and glass, without 10 cast-iron or wood, are employed in the construction of the car-body, thereby furnishing a car which combines the greatest strength with the requisite lightness, and which will be fire-proof.

As car-bodies are now and have been for 15 many years constructed, they are liable to telescope in collisions, to easily be broken in accidents, and to be burned from various causes, to the great injury and loss of life of the passengers, while the material of which they are 20 built and the manner in which they are constructed circumscribe their dimensions and carrying capacity.

The object of my invention is to construct 25 a car-body in which all the necessary conditions to prevent the aforesaid liabilities are to be found, and which can with safety be made larger and with a greater carrying capacity.

Figure 1 is a side elevation of a section of 30 my improved car-body without outside shell. Fig. 2 is a floor plan. Fig. 3 is a vertical cross-section. Fig. 4 is an end elevation. Fig. 5 is a sectional detail.

In the accompanying drawings, which form 35 a part of this specification, A represents the sill plates, made of bar steel or iron, the length of the car-body. Upon these side plates the transverse girts B are laid at proper intervals, as shown in Figs. 4 and 5. These girts are also 40 steel or iron bars, and upon them are placed the trusses C, also bars, and a suitable bolt or rivet secures the ends of the girts and trusses to the side plates. A post, D, suitably secured at top and bottom, is placed between the girt and truss, midway of their length, except 45 nearest the ends of the car, where two posts, a, are employed, one on each side of the center, to give room for placing and operating the draw-bar.

E is a plate, running from end to end of the 50 car centrally and below the girts, and the posts D are made with a riveting-pintle, b, at

each end. The bottom pintle passes through the girt and plate E and is riveted thereto, while the upper pintle passes through the truss C and is riveted thereto. The next step is to 55 prepare the zigzag rail or web F and rivet each of the lower bends to the sill-plates, midway between the girts. Upon the upper bends of the rails F are then laid the girts G, each of the ends of which is provided with an offset, 60 c. Upon the top of these offsets are then placed the longitudinal chords H, upon which are laid the zigzag rails I, the lower bends of which are placed in opposition to the upper bends of the rails F, and there rivets are used 65 to secure the rails and plates F, G, H, and I together. Then upon the top of the rail I is laid the chord J, upon the top of which are set the posts K, each of the ends of which is provided with a pintle similar to those on the posts D. The 70 lower pintle passes through the rail J and the upper bends of the rail I and is riveted thereto. The upper pintle passes through the top plate, K', and is riveted thereto. The spaces L are to be utilized for windows. The girts G are 75 riveted to the top of the trusses C, and the floor M, of rolled plates, is riveted to the girts G between the offsets c. The chord K' is overlaid by the wall-plate L, leaving an open space between it and the chord, which space may be 80 utilized for the purposes of ventilation, or K' and L may be formed of one solid bar. The rafters N, for the roof, are formed in one piece of any desired shape, and are riveted to the wall-plate by means of the pintles on the upper ends of the posts K. The corners of the car are formed by the posts O, riveted to the top and bottom chords by pintles. A door is formed at each end of the car, to which access is had from the usual platform formed by the 85 extension of the car-floor. Proper offsets in the car-floor are provided to allow the necessary movement of the car-wheels, the construction and operation of which I have described in a separate application. The boxes in which the 90 axles run are contained within the floor of the car-body, while the upper portions of the wheels project through the floor into the interior of the car, where they will be protected and hid from view by a proper arrangement of seats. 95

It will be seen that by the above-described construction I make use of very simple mem-

bers, which require no skilled labor in their erection, while all accidents can only be local, owing to their cellular construction.

What I claim as my invention is—

5 1. The composite car-floor support herein described, consisting of two sets of chords A H, and webs F, arranged one at each side of the car and forming the sides, in combination with the lateral trusses connecting them together, and to which the flooring is secured, substantially as specified.

10 2. A car-body having each of its sides constructed of chords J H, continuous unbroken web I, posts K, and chords K', in combination with the floor-supports, substantially as described.

15 3. In a car, a truss consisting of the parallel girts B G, truss C, and post D, the girts G being provided with offsets e for the purpose of

confining and supporting the floor M, substantially as specified.

4. In a railway-car consisting of a series of like subdivisions formed of simple longitudinal chords arranged in pairs one above the other at each side of the car, intermediate webs and transverse trusses, substantially as set forth.

5. A composite car-floor frame constructed of two sets of chords, A H, and webs F, forming the sides thereof, and the central chord, E, and lateral trusses B C G, connected to all the chords, forming the bottom thereof, substantially as described.

THEO. LUCE.
